UNITED STATES PATENT OFFICE.

JAMES H. DENNEDY, OF DETROIT, MICHIGAN.

PRESSURE-CONTROL DEVICE FOR SWITCHES.

Application filed June 29, 1922. Serial No. 571,880.

To all whom it may concern:

Be it known that I, JAMES H. DENNEDY, a citizen of the United States, residing at Detroit, county of Wayne, State of Michigan, have invented a certain new and useful Improvement in Pressure-Control Devices for Switches, and declare the following to be a full, clear, and exact description of the same, such as will enable others skilled in the art to which it pertains to make and use the same, reference being had to the accompanying drawings, which form a part of this specification.

This invention relates to pressure controlled switches for refrigerating systems or other apparatus carrying a fluid under a variable pressure, and the object of the invention is to provide a switch mechanism and apparatus for operating the switch controlled by the pressure of fluid as for instance the fluid in the low pressure side of the circulating system for an artificial refrigerating apparatus. The particular features of the invention are involved in the structure and relationship of parts of the control mechanism subject to influence of variation of pressure and in the combination therewith of an electric switch for making and breaking the circuit of an electric motor operating the apparatus. These objects and the several novel features of the invention are hereinafter more fully described and claimed, and the preferred form of construction of a device embodying my invention is shown in the accompanying drawings in which—

Fig. 1 is a vertical longitudinal section of my improved switch and control apparatus showing the switch open.

Fig. 2 is a similar view showing the switch closed.

Fig. 3 is a plan view of the switch mechanism.

In the usual artificial refrigerating system, a compressor is utilized in conjunction with a circulating system having a high and low pressure side and an electric motor for operating the compressor. This structure embodies the combination with a switch device for making and breaking the circuit of a motor of apparatus subject to influence of variation in pressure of the low pressure side of the circulating system and while the refrigerating system in its entirety has not here been shown the operation of the device will be readily understood by those familiar

with the art. The low pressure line of the circulating system is indicated at 1 and a branch 2 leads from this line to the casing 3 of the control device. Within this case is a deeply corrugated cylindrical bellows member 4 known to the trade as a "sylphon," the lower end of which is sealed to a plate 5 and the upper end of which is sealed to a plate 6 that is securely fastened between the cap member 7 and the flange 8 of the casing 3. This provides a chamber 9 between the bellows member and wall of the member 3 sealed to atmosphere into which the line 2 opens. It is to be observed that I have shown the line 2 as being the low pressure side of the circulating system of artificial refrigerating apparatus whereby the chamber 9 is subject to variation in pressure, but it is to be understood that any approved means may be employed to vary the pressure in the chamber 2 by a temperature change as for instance the well known method of supplying a volatile fluid in the chamber vaporizing under certain high temperature and condensing under low temperature or the usual sensitive bulb may be employed connected to the apparatus in the same manner as here shown with the line 2. The plate 5 at the lower end of the bellows member is secured and sealed to the central shaft 10 which extends upward through a threaded plug 11 in the upper end of the cap member. This member 11 is provided with a central square or hexagonal aperture 12 and the shaft is threaded to receive a nut 13 flanged at the lower end as shown and having a square or hexagonal body that may enter the aperture 12 of the plug 11. The threads on the outside of the plug 11 and the threads on the inside of the nut 13 have the same pitch and number of threads per inch. The plug 11 is preferably provided with a series of apertures 14 for insertion of a pin to be utilized in turning the nut or plug, and the plug 11 and nut 13 provide for an adjustment without altering the relative positions of plug 11 and the nut 13 as is hereinafter stated. Within the bellows member and about the shaft 10 is a coiled compression spring 15 seating against the plate 5 at the bottom and in the plug 11 at the top and tend to force the member 5 downward expanding the bellows member. The switch is so constructed that this movement downward by the spring forces the shaft 10 downward due to its attachment to the bellows

member and opens the switch and on the contrary pressure developing in the pipe line 1 and chamber 9 forces the plate 5 upward against the tension of the spring 15 compressing the bellows raising the shaft 10 which closes the switch.

The character of the electric switch structure is not material to this invention as various structures can be utilized that will 10 make or break the circuit by movement of the shaft 10. The preferred type of switch here shown comprises a base 16 of insulating material that is carried on the cap member 7 by means of studs 17 of which there 15 are several. On this base is mounted a frame consisting of the side plates 18 and 19 as will be understood from Fig. 3. A shaft 20 extends through the two side frames at one end and on the outer side of each frame 20 is pivotally mounted a lever 21 formed at the rear end with outturned flanges 22 and 23 in V form and also with terminal outturned flanges 24 and 25. The end 26 of each lever 21 is adapted for engagement with 25 the respective contact member 27 or 28 as the case may be, there being two levers 21 and a contact member 27 and 28 for the respective levers. The circuit 90, 91 of the 30 electric motor is connected with these contacts 27 and 28 and when the end 26 of the levers 21 is passed between the blades of the members 27 and 28 the circuit is completed. The levers 21 are operated by the 35 U member 29 pivotally mounted on a shaft 30 extending through the two frame members 18 and 19 and the ends 31 of this member 29 lie between the flanges 22, 23 etc., of the levers 21. The cross member of the U extending between the legs thereof has an 40 aperture and in this aperture extends a pin 32 pivotally mounted at 33 to a pivoted lever 34. A coiled spring 35 extends about this pin and between the shank of the pin and the bar of the member 29. This lever 34 is 45 pivoted to the shaft 20 between the side frames and in fact, as here shown, this member 34 is formed of two duplicate parts as will be understood from Fig. 2 and the head of the pin 32 extends between the adjacent 50 ends of these two parts of the levers 34 as will be understood from Fig. 3. Near the pivot point of the lever 34 is a shaft 36 extending between the two parts of the lever 34 and pivotally mounted on this shaft 55 and extending downwardly therefrom is a link 37 which is pivotally connected at 38 with a link 39 which in turn is pivoted at 40 to a link 41 pivotally supported on the shaft 30. There are preferably two links 60 39 and supported therebetween is a shaft 42 on which is pivotally mounted the threaded stub shaft 43. The upper end of the shaft 10 of the control device, as will be understood from Fig. 1, has a threaded portion 44 and a right and left hand threaded 65

nut 45 is provided into which this end 44 of the shaft 10 and the threaded end of the shaft 43 extend thus connecting the links 39 with the shaft 10.

The two part lever 34 above mentioned has 70 an arcuate slot 45 near the end to which the pin 32 is pivoted and through this slot extends the shaft 30 and which limits the movement of the composite lever 34 on its pivot. With the parts in the position shown in Fig. 75 2, pressure in the line 1 has raised the plate 5 and shaft 10 closing the switch and completing the circuit. This movement of the parts is from the position shown in Fig. 1 to that shown in Fig. 2. It will be seen on 80 examining Fig. 1, that on upward movement of the shaft 10 due to its connection by means of the stub shaft 43 with the links 39 and the links 37, the lever 34 would be gradually moved upward about its pivot. This movement raises the pivot point 33 of the pin 32 upward compressing the spring 35 and as this pivot point passes the center line between the aperture in the yoke member 29 and shaft 30 thereof, the spring will act 85 to depress the end of the yoke 29 raising the opposite end 31. Due to the flanges 24 and 22 the end 31 of the member 29 by engaging first against the flange 24 begins to turn the lever 21 and then engages the flange 22 comparatively close to the pivot 90 point of the lever 21 which causes a quick movement of the end 26 in engaging the contact 27. This action of the ends 31 of the yoke in relation to the levers 21 is the same 95 either in the upward or the downward movement. The upward movement is caused by pressure in the line 1 which closes the switch 100 of the motor and starts the compressor into operation. This starting of operation of the 105 motor and pump begins to decrease the pressure in the line 1 until the spring 15 overcomes the pressure moving the plate 5 and shaft 10 downward and opening the switch 110 causing cessation of operation of the motor and pump.

The nut 13 may be moved upward or downward on the shaft 10 and it is to be understood that when the shaft and plate 5 are in the lowermost position the flange 115 of the nut 13 is below the web of the plug 11. This flange limits the upward movement of the shaft 10 and plate 5 so that excess pressure in the line 1 cannot be transferred to the switch mechanism and by adjustment of the plug 11 and nut 13 required latitude of movement of the switch is provided and the mechanism safeguarded from pressure. The plug 11 is made adjustable to vary the 120 tension of the spring 15. Also the bellows member is prevented from too great elongation or compression as the plate 5 limits the expanding movement of the bellows member and the nut 13 of the compression movement. I have here shown and described a particular 125 130

switch structure. As heretofore stated it is to be understood that various switch structures may be utilized with this control device and it is also to be understood that the switch structure may be arranged to break the circuit on an increase of pressure and to close the circuit on a decrease of pressure in the chamber 9 which is exactly the reverse of the operation of the switch here shown and described.

With a device of this character, control of the operation of the artificial refrigerating apparatus or other devices is secured by a structure that is simple and efficient in character and when used with artificial refrigerating apparatus, temperature may be controlled by variation in pressure of the low pressure line or expansion side of the system rather than by use of a thermostat as has ordinarily been the practice. By setting this mechanism to close the switch upon certain increase of pressure in the low pressure line the pressure of the low pressure line is maintained between certain limits which determines the cooling effect. Furthermore, by use of the specific switch mechanism as herein described, a slight movement of the shaft 10 may cause the maximum movement of the switch arm 21. This occurs by reason of the peculiar leverage utilized and in the particular relationship of the actuator member 31 and the lever 21 causing a quick make or break of the contact. However, my pressure actuated device may be used with various types of apparatus in which it is necessary or useful to make or break a circuit upon decrease or increase in pressure of a fluid subject to variation in pressure.

Having thus fully described my invention, what I claim is—

1. In pressure actuated mechanism for control of electric switches, the combination with an electric switch having a member movable to make or break a circuit through the switch, of a pressure controlled mechanism for moving the member comprising a casing, a bellows like member therein expandible or contractible longitudinally and providing a chamber on the exterior thereof sealed to atmosphere and open to influence of fluid having a variable pressure, a rod secured to an end of the bellows member, a cap for the casing supporting the switch, said cap having an opening therethrough whereby the interior of the bellows member is open to atmosphere, the rod extending through the said aperture to a movable part of the switch and being threaded, a nut on the rod adjacent the said aperture adjustable longitudinally of the rod and limiting the extent of compression movement of the bellows member whereby the switch mechanism is protected from excess pressure, and a coiled spring within the bellows member

tending to expand the same on certain reduction of pressure in the chamber.

2. In pressure actuated mechanism, the combination with a device movable under control of said mechanism, of a casing comprising a body portion and a cover, a cylindrical corrugated bellows within the casing having one end in sealed attachment to the cover, a plate closing the other end of the corrugated bellows member, a rod attached to said latter closing member and extending outwardly through an aperture in said cover, said aperture providing atmospheric communication to the inner part of said corrugated member, an adjustable member fitted in the aperture in said cover, a compression spring between said adjustable member and said plate, said adjustable member having an aperture therein through which said rod extends, a second adjustable member carried by the rod and arranged to abut the inner side of the adjustable member carried by the cover, said plate being normally held against the base of said casing by said spring, and means for applying fluid pressure between said corrugated bellows member and said plate for causing the reciprocation of said rod between the before mentioned stops.

3. In pressure actuated mechanism for control of electric switches, the combination with a switch having a member movable to make or break a circuit through the switch, of a casing, a bellows like member therein having one end secured to the casing, the opposite end being closed and providing a chamber between the member and casing sealed to atmosphere, a cap for the casing having an aperture providing atmospheric communication to the inner part of said bellows like member, an apertured plug therein in threaded relation with the cap, a coiled compression spring extending between the plug and closed end of the bellows, a rod secured to the closed end of the bellows member and extending through the aperture of the threaded plug, said plug providing a means for adjusting the tension of the spring, a member on the shaft adjustable longitudinally thereof and limiting the extent of movement of the rod on compression of the bellows member whereby the switch mechanism is relieved from excess pressure, said rod being attached to the movable switch member.

4. In mechanism for controlling an electric circuit in combination with a switch having a member movable to make or break the circuit, of apparatus for causing movement of the member comprising a rod connected with the movable member, a bellows like member expandible or contractible by variation in pressure, said rod being connected with the said member, a casing enclosing the bellows member and providing

a chamber between the member and the wall of the casing, a cap member for the casing through which the shaft extends, a plug threaded therein having a many sided central aperture, a nut threaded on the rod, the plug and nut having the same pitch and number of threads per inch, the nut having a many sided portion extending into the aperture of the plug whereby turning of the plug turns the nut to like extent, said

nut having a flange normally spaced from the plug permitting limited movement of the rod by contraction of the bellows member, and a spring extending between the plug and base of the bellows member adjustable in tension by the turning of the plug. 15

In testimony whereof, I sign this specification.

JAMES H. DENNEDY.
